(57) **CLAIM**

The ornamental design for a swimming pool entry deterrent, as shown and described.

DESCRIPTION

FIG. 1 is a perspective view of the swimming pool entry deterrent of the instant invention in an open position;

FIG. 2 is a perspective view the swimming pool entry deterrent of the instant invention in a folded/storage position;

FIG. 3 is a front elevational view of the FIG. 1;

FIG. 4 is a rear elevational view of the FIG. 1;

FIG. 5 is a top plan view of the FIG. 1;

FIG. 6 is a bottom plan view of the FIG. 1;

FIG. 7 is a left side elevational view of the FIG. 1; and,

FIG. 8 is a right side elevational view of the FIG. 1.

The broken lines in the drawing depict environmental subject matter and form no part of the claimed design.
